UNITED STATES PATENT OFFICE

MARCEL CASSÉ, OF ESSONNES, FRANCE

HAT-SHAPING MACHINE

Application filed June 7, 1929, Serial No. 369,115, and in France June 20, 1928.

This invention relates to hat-shaping or blocking machines comprising a block or form, on which the hat blank is adapted to be stretched by means of a reciprocable collar engaging the hat blank between said block and a number of clamping members adapted to clamp the edge of the hat blank. Said collar is further adapted to form the joint line between the brim and the hat crown or bell and to make the rim properly flat.

This invention has for its object to provide an improved hat shaping process whereby the material of which the hat blank is made will be heated and cooled throughout its mass by means of currents of heating or cooling fluids circulating through perforations of the block and through the hat blank; it has also for its object to provide a process whereby the hat is fixed in shape on the block, by extending the heating period for a certain time after the hat has been stretched on the block.

The invention has also for its object to provide improved stretching means embodying a deformable collar adapted to form the joint line between the hat bell and brim at the proper place, and without producing an excessive stretching of the bell portion of the hat blank.

A further object of the invention is to provide an improved block and process of manufacturing the same, whereby an abundant mass of fluid may be circulated through the hat blank in a relatively short time; another object is to provide a block of inexpensive manufacture and very accurate shape.

A still further object of the invention is to devise an improved machine which operates automatically and requires little attention from the operator, of a reliable and economical construction, and whose efficiency and output are materially improved with respect to the known machines.

Further features of the invention will be specified in the following description, with reference to the appended drawings, given solely by way of example, and in which:

Fig. 1 is a cross-section on the line 1—1 of Fig. 4, showing in sectional elevation an im-

proved hat-shaping machine according to the invention.

Fig. 2 is a cross section on the line 2—2 of Fig. 4, showing part of the mechanism in side elevation.

Fig. 3 is an elevational view, partly in section, showing the driving and clutch mechanisms.

Fig. 4 is a horizontal section on the line 4—4 of Fig. 3.

Fig. 5 is a partial section of the joint line forming collar.

Figs. 6 and 7 are views similar to Fig. 5, illustrating the deformation of the collar in operation.

The hat shaping machine illustrated in the drawings essentially comprises a block or form 4, on which the hat blank is adapted to rest, a number of clamping members 100 arranged in a circle about said block and adapted to clamp the edge of the hat blank 1; a collar 15 adapted to engage the hat blank between the block 4 and the clamp 100; a heating bonnet 70 adapted to cover the hat blank on the block, and suitable mechanisms for controlling the above mentioned parts.

The block 4 illustrated in Fig. 1 is made of minutely perforated sheet metal such as copper, Monel metal or the like. It is preferably shaped from a sheet of such metals, of about one millimeter thickness, perforated with holes which are as minute as possible. From this sheet or blank is cut the lateral wall and the top, the latter being suitably stamped. The lateral wall and the top are then brazed together or are preferably welded by the autogenous process, and the resulting rough block is shaped by the hammer or press. The shaping or stamping by the press is preferably effected in the mould used with the hydraulic press, in which the hats to be blocked are subsequently pressed. The surface of said block may be tinned, or may be plated with nickel, chromium or the like. The lower edge of said block is soldered to a ring 4^a.

The block thus prepared is laid on a perforated base 5, optionally curved and supported by a cup shaped support 7 having bosses 7^a and studs 7^b engaging apertures of ring 4^a, whereby the block 4 may be readily

laid and centered on base 5. The chamber 6 formed between base 5 and support 7 has an annular groove 28 into which opens a steam supply pipe 8 and is provided at its centre with a seat 29 for a valve 14 whose rod 31 is guided through a spider guide 32. Support member 7 is mounted at the upper end of a vertical conduit 33 of large cross-section. The lower end of conduit 33 opens into a hollow connecting member 34, which is suitably curved and to which is attached a flexible hose 35 (Fig. 4), opening into and secured to a suitable receptacle 35^a, in which a vacuum is produced by any suitable means such as a fan, an ejector operating with steam or compressed air, a pump, or the like.

Connecting member 34 is secured to a depending tube 36, and the unit comprising block 4, member 7, conduit 33, member 34 and tube 36 is slidably mounted in a guiding member 37 secured to the lower face of a table 25 supported by two spaced vertical plates 26-27, table 25 and plates 26-27, forming the machine frame.

Guiding member 37 is hollow and comprises a vertical slot 42 through which extends a projection 38 of connecting member 34, said projection moving along said slot in the vertical motion of member 34. The opposite face of member 37 is provided with a larger slot, through which extends the curved portion of connecting member 34, the latter moving along said slot in the movement of member 34.

Both sides of slot 42 are formed with reinforcing ribs 42^a ending in bosses 41^a which receive a pivot pin 41, to which is pivoted a pawl 39, having an outwardly extending portion 40 forming an actuating handle. When projection 38 engages pawl 39, as shown in Fig. 1, the vertically movable unit 4-7-33-34-36 is held in an elevated position. To release the latter and allow the downward movement thereof, handle 40 is turned upwardly to release projection 38.

Member 34 is provided with a lower flange portion 43 adapted to enter a corresponding recess 44, formed at the base of member 37, when the pawl is released, thereby damping the shock when tube 36 reaches its lower position.

Within tube 36 is slidably mounted a plunger 45 secured to the lower end of rod 31; a spring 46, bearing against the lower face of member 34 and the upper face of plunger 45, urges rod 31 and valve 14 downwardly to apply valve 14 against its seat. Plunger 45 bears at its lower end on a roller 47 supported by a crank lever 48, pivotally mounted on a shaft 49 carried by the machine frame. At its opposite end, said crank lever carries a roller 50, engaging a cam member 51, keyed to a driving shaft 52. It will be seen that the rotation of the cam in the direction of arrow f¹ (Fig. 1) causes a

rocking motion of lever 48, whereby roller 47 lifts plunger 45 and hence raises valve 14 from its seat.

At the lower end of tube 36 and on either side thereof are mounted rollers 53, engaging the upper faces of two balance levers 55 and 56. Both levers are loosely mounted on shaft 49 and are rigidly connected together by means of cross rods 57 and 58. Lever 55 is substantially rectilinear, as shown in Fig. 1, and carries at its front end a counterweight 55^a. Lever 56 has a straight front portion having a similar counterweight 56^a, while its rear portion has substantially the shape of a segment and its inner edge is formed with a curved recess 56^b adapted to receive a correspondingly curved projection 60^a of a cam 60 mounted on shaft 52 (for the angular position of said cam shown in dot-and-dash lines), an angular recess 56^c adapted to receive an angular projection 60^b of cam 60, and a projecting bracket 56^d adapted to be received in the recess of said cam between projections 60^a and 60^b; said bracket 56^d carries a roller 59 cooperating with cam 60. Cam 60 comprises a circular raised portion having a series of notches 61 on a portion of its periphery. The lower portion of said cam is connected to the raised portion by a rounded surface bounding projection 60^a and a straight radial edge bounding projection 60^b. It will be seen that the rotation of cam 60 in the direction of arrow f², from the position shown in full lines in Fig. 2, will first leave levers 55 and 56 in the position shown. Then roller 59 will move toward shaft 52 into the recess of cam 60, thus allowing the downward movement of counterweights 55^a, 56^a and block 4; then roller 59 will ride over the curved edge of projection 60^a, thus lowering the rear end of levers 55-56 and restoring the block into the position shown in Fig. 1; a further rotation of cam 60 produces a jerked motion of levers 55-56 and hence of block 4, due to notches 61.

To cross rod 58 is pivoted an upwardly extending rod 63, slidable in a hole of a transverse rod 64, pivoted between the spaced walls of a bracket 65, mounted at the lower end of a column 66; a spring 62 bearing on rod 64 and on a nut 62^a screwed on rod 63, provides a yielding connection between levers 55-56 and column 66. The rocking motion of levers 55-56 produces a reciprocating motion of column 66, guided in a bracket 67 secured above table 25.

At the upper part of column 66 is loosely mounted the hub 69^a of an arm 69, said hub having locking members 68 adapted to lock said hub in any suitable angular and axial position on column 66. The inner end of arm 69 is enlarged and has an aperture in which is mounted a bonnet 70 adapted to cover block 4 in the lower position of column 66.

Within bonnet 70 is mounted a coiled tube 71 connected with a set of radiating tubes 73, mounted transversely adjacent the upper opening 72 of said bonnet. Said radiating tubes and said coil tube are supplied with steam through a flexible pipe 86; they may also be heated by means of an electric resistance.

The enlarged end of arm 69 is provided with an annular flange 69^b, to which are secured a number of depending rods 16, connected at the lower end to a ring 16^a; between said ring and a lower ring 17 is clamped a collar 15 of elastic material (Fig. 5).

The elastic collar 15 is oval or circular, according to the shape of the block. When inoperative, it has a truncated lower face, as shown in Fig. 5, and it is adapted to engage the hat blank by its free edge 18, whose periphery is considerably larger than that of the corresponding base portion of the hat block 4. When the hat form or block 4 and its supporting parts are raised during the hat shaping operation, bonnet 70 is lowered together with the elastic collar 15. Due to the resistance of the hat and to the elasticity of the collar 15, the said collar will be deformed, as shown in Figures 6 and 7, whereby its edge 18 comes nearer the block 4 and the perimeter of the said edge becomes smaller; however, the material forming the collar and the cross-section of said collar are such that this perimeter, during the whole operation, will still exceed that of the hat in spite of this diminution. In this manner, the whole side of the hat (Fig. 1) will be drawn out or stretched. When the hat, in contact with the edge 18 of the collar 15, engages the perforated plate 5, the collar 15 will be further deformed due to the further lowering movement of the rigid collar 16^a and will press the rim of the hat upon the perforated plate 5. This bending further reduces the perimeter of the edge, and the latter presses the rim of the hat against the block 4, at the joint line with the brim.

Steam is admitted through a pipe 74 (Fig. 2) into a water separator 75, which preferably also comprises a set of tubes 76 or a coil tube arranged circularly around a central chamber, through which extends a gas burner 77 or a heating resistance supplied with electric current. Steam passing through tubes 76 is superheated and well dried.

The upper part of separator 75 is connected with pipe 86 supplying bonnet 7 while its lower part is connected with pipe 8, provided with a valve 78. The rod 83 of said valve is pivoted at its lower end to a lever 81, fulcrumed in a bracket 82 secured below table 25 and having an outwardly projecting handle 85. The other end of lever 81 is pivoted to the upper end of a fork lever 80, which straddles shaft 52 and carries a roller 79^a adapted to cooperate with a cam 79, keyed to

shaft 52. It will be seen that the closing and opening of valve 78 is thus controlled by the rotation of shaft 52 and cam 79, and that said valve may also be actuated by hand by means of handle 85.

The machine is driven by shaft 52, to which is keyed a large gear wheel 87 (Fig. 3) mounted in a casing 87^a bolted to plate 27, said wheel meshing with a worm gear 88 mounted on a shaft 88^a at the outer end 75 thereof is loosely mounted a driving pulley 89. The inner surface of said pulley forms a clutch cone adapted to cooperate with a clutch member 90, slidably mounted on shaft 88^a and rotatable therewith by means of an elongated key 88^b. Integral with member 90 is a hollow sleeve 90^a containing a spring 88^c, adapted to urge member 90 into the clutching position. Sleeve 90^a is provided with a peripheral groove, adapted to be engaged by a fork 91 secured to a shaft 91^a, to which is also secured a bracket 92^a; a swivel 92^b extends through said bracket and the branches of a fork 92^d formed at the lower end of a clutch operating lever 92. Said lever carries a roller 94, adapted to cooperate with a cam member 93 keyed to shaft 52. It will be understood that rotation of shaft 52 in the direction of arrow 71 (Fig. 1) causes the clockwise rotation of lever 92 about shaft 91^a into the unclutching position. If it is desired to relieve the clutch from the action of cam 93, lever 92 is pivoted about swivel 92^b away from plate 27 (Fig. 4) against the action of a spring 92^a, attached to lever 92 and to casing 87^a. The angular setting of cam 93 with regard to cam 60 is such that the automatic unclutching of clutch 89—90 by cam 93 is produced at two instants, viz:

When the parts are in the position shown in Fig. 1, that is, when the stretching of the hat is completed; and at the end of the operative cycle of the machine, when bonnet 70 assumes its uppermost position.

Referring now to the clamping members, these are constructed and actuated in the following manner:

On table 25 is arranged a circular row of U-shaped brackets 94, coaxial with block 4 (Fig. 1), and arms 96 are pivoted to said brackets by means of pins 95. Each arm carries at its upper end a pivot pin 99, to which is pivoted a clamping jaw 100, whose front portion 98 is adapted to cooperate with the upper face of arm 96, to clamp the edge of the hat-blank, a projection 101 forming a stop to position the edge of the hat blank.

Each upper jaw 100 is pivoted to a curved fork 102, secured to a rod 103, pivoted at 105 to a small bracket 106, secured to an annular plate 107. Said plate is mounted on two uprights 108 (Fig. 3) located on either side of the machine and which are guided vertically in guides 109 secured to the underface of table 25. The lower ends of uprights 108 are

pivotedly connected to the upper ends of small rods 110 whose lower ends are pivoted to respective straps 111; each strap has an aperture 112 with two parallel straight faces 113 and is loosely pivoted to an eccentric journal 114 of a shaft 115, pivotally mounted in plates 26-27. To shaft 115 is keyed a lever 116 (Figs. 3 and 4) having at its upper part a nut 117, engaging a screw 118 to the outer end whereof is secured a hand wheel 119. Said screw 118 is journaled in a member 120, rotatably mounted in plate 27, and adapted to prevent axial movement of screw 118.

In the openings 112 of strap 111 are rotatably mounted respective cam members 121, secured to the ends of a shaft 122, to which is secured an operating lever 123. To shaft 122 is also keyed an arm 124 (Fig. 2), pivoted at 125 to a lever 126, whose forked end straddles shaft 52 and which carries a roller 128, adapted to cooperate with a cam member 129, keyed to shaft 52; said cam 129 is adapted to move lever 126 lengthwise and to cause the automatic release of the clamping members at the end of the operative cycle of the machine by rotating shaft 122 and cam members 121 in the direction of arrow f^2 (Fig. 3) to raise the uprights 108 and rods 103.

The lower end of each arm 96 is provided with a block 130 (Fig. 1) having upper and lower curved surfaces 131 and 132, whose radii are R^1 and R^2 . Said blocks are adapted to engage the inner plane faces of discs 133 and 134 which are rigidly connected together. Small springs 135, bearing on table 25, and on the lower face of arm 96, are adapted to urge the blocks 130 against disc 133. The radii R^1 of the several curved surfaces 131 are such that all the clamps are disposed in a circle when blocks 130 engage disc 133.

In the stretching operation, which is produced by the lowering movement of collar 15 and the upward movement of block 4, the edge of the hat blank is drawn toward the centre, whereby arms 96 are caused to pivot about pins 95, and blocks 130 engage disc 134. The radii R^2 of the several surfaces 132 are such that, when blocks 130 engage disc 134, the various clamping members are then arranged in an oval. It will thus be seen that the clamping members which clamp the circular edge of the hat blank stretch the latter into an oval.

Disc 134 is mounted on two rods 136, located on either side of the machine, and guided vertically in guides 137 (Fig. 2) secured to the underface of table 25. Each rod 136 is provided with two spaced flanges 136^a and 136^b, embracing a rounded part 138^a at the end of a lever 138, pivoted to a shaft 139. The opposite ends of levers 138 are connected together by a rod 140, connected by a rod 141 to a pedal lever 142, pivoted to the frame at 143, and having a counterweight 144; said counterweight tends to raise rod 141 and to

lower members 136 and disc 134, thus urging the clamp members toward the centre of the machine.

To shaft 139 is keyed a sector 145, having a notch 146, adapted to be engaged by a pawl 147 on a lever 148, pivoted to rod 140. It will be seen that, when pawl 147 engages notch 146, rod 140 becomes rigidly connected with sector 145 and hence with shaft 139. To shaft 139 is also keyed an arm 149 (Fig. 2) whose upper end carries a nut 150 engaging a screw 151, provided with a hand-wheel 152 (Fig. 4); said screw is journaled in a bracket 153 (Fig. 4) pivoted to plate 26 and which prevents axial displacement of screw 151.

Rotation of hand-wheel 152 causes rotation of shaft 139 and sector 145, for adjusting the angular position of notch 146, and hence the vertical position assumed by disc 134 when pawl 147 engages said notch.

The operation is as follows:

The machine being at rest, cam 60 assumes the position shown in dot-and-dash lines in Fig. 1, whereby bonnet 70 is in its uppermost position and block 4 in its lowermost position. Block 4 is held in this position by the engagement of pawl 39 below projection 38. Pawl 147 is disengaged from notch 146, whereby pedal 142 is raised by counterweight 144 and the clamping members 100 are disposed in a circular row near the centre of the machine. Lever 123 assumes the position shown in Fig. 3, whereby uprights 108, plate 107 and rods 103 are elevated and the clamps 100 are open.

The hat blank 1 is presented above block 4 and the edge thereof is engaged into the clamps, the latter being brought to a suitable distance from the vertical axis of block 4 by depressing pedal 142 against the action of counterweight 144 and releasing pedal 142 until projections 101 engage the edge of the hat blank. By drawing lever 123 to the left (Fig. 3), cam 121 depresses strap 111 and lowers plate 107, thus bringing the clamps into the clamping position. The amount of clamping pressure may be adjusted according to the thickness of the hat blank, by rotating hand-wheel 119, thus moving nut 117 along screw 118 and rotating the eccentric journals 115. This adjustment alters the position of the axis about which strap 111 is rotated, and hence the vertical stroke of uprights 108.

Pedal 142 is then further depressed, thus raising discs 133 and 134, whereby arms 96 are rocked in the direction of arrows f^3 (Fig. 1), which produces the stretching of the hat-blank into an oval shape, as above explained.

This movement of arms 96 is continued until pawl 147 snaps into notch 146, the angular position of which has been adjusted by actuating hand-wheel 152, thus conforming the position of the clamping members with the size to be given to the hat brim.

Clutch lever 92, which assumes its upper-

most position due to roller 94 engaging the raised portion of cam 93, is then pivoted away from the machine about swivel 92^b. Spring 88^c urges sleeve 90^a into the clutching position, and, as soon as released, lever 92 is urged back against plate 26 by spring 92^a.

The machine being thus started, cam 60 is rotated from the position shown in dot-and-dash lines in Fig. 1 in the direction of arrow 10 f¹ and roller 59 rides over the curved portion 60^a of cam 60; levers 55—56 are rocked from the position shown in dot-and-dash lines into the position shown in full lines, thus raising members 36—34—33—7—5 and block 15 4 (Fig. 1), while lowering column 66, bonnet 70 and collar 15. At the beginning of this movement cam 79 (Fig. 2) raises roller 79^a lever 80 and rod 83, thus opening valve 78, whereby steam is admitted into block 4. The 20 movement of block 4 and bonnet 70 takes place in a jerked manner, due to the notches 61 of cam 60.

When block 4 has reached its uppermost position, collar 15 presses the hat brim against base 5 in the manner above described and bonnet 70 surrounds the bell portion of the hat; at this instant, cam 93 raises roller 94 and lever 92, which pivots about shaft 91^a, thus unclutching the machine. Block 4 is held 30 in its upper position by pawl 39, valve 78 is still in its open position, and hence the steaming of the hat, stretched on block 4, is continued as long as shaft 52 is at rest, due to the unclutching of the machine. Superheated steam supplied through pipe 8 escapes through the perforation of base 5 and block 4, and through the hat blank.

The steaming is continued for a given period, which depends on the temperature of the steam, on the thickness of the hat blank and on the material of which said hat is made, in order to fix the shape of the hat; the coiled tube 71 serves to heat the bonnet and maintain the temperature within the latter above 100° C. Then, the operator again moves lever 92 away from the machine about swivel 92^b, and spring 88^c again clutches the machine. In the initial movement of shaft 52, the raised portion rotates past roller 79^a, whereby lever 80 is lowered, thus closing valve 78 and stopping the steam supply; simultaneously, cam 51 raises roller 50, thus rocking lever 48 about shaft 49 and raising plunger 45, rod 31 and valve 14. Roller 59 still engages the circular portion of cam 60, whereby the block and the bonnet remain in the position shown in Fig. 1. Due to the opening of valve 14, an abundant mass of air is impelled through the opening 72 of bonnet 70, through the hat blank, the perforations of block 4 and base 5, chamber 6, conduit 33, member 34 and flexible hose 35 into vacuum tank 35^a. This current of air, which is heated to the required temperature by radiator 73, dries and cools the hat blank.

Upon a further rotation of shaft 52, the raised portion of cam 60 rotates past roller 59, whereby levers 55 and 56 are again rocked into the position shown in dot-and-dash lines in Fig. 1. Bonnet 70 is raised, block 4 is lowered, and valve 14 is closed by the action of spring 46. Simultaneously, cam 129 raises roller 128 and shifts lever 126 to the left (Fig. 2) thus rotating shaft 122 and cam 121 (Fig. 3); straps 111 oscillate about journals 115, to raise plate 107 and rods 103, thus releasing the clamps 100. When these movements are completed, cam 93 again raises roller 94, to unclutch the machine. The whole mechanism is restored into its initial position, and the hat, which is stretched, fixed in shape, dried and cooled, may be removed from the machine by the operator.

Obviously, the invention is not limited to the details of construction herein described and represented which have been given only by way of example.

For instance, collar 15 may be made of a rigid material; the air current may also be produced by an over-pressure in bonnet 70, instead of a vacuum within block 4.

Having now described my invention what I claim as new and desire to secure by Letters Patent is:

1. In a hat shaping machine, a perforated block adapted to receive the hat blank, means for circulating steam through said block and hat blank, means for circulating air through said block and hat blank, means for stretching the hat blank on said block 100 and means operatively connected with said stretching means for controlling said air and steam circulating means.

2. In a hat shaping machine, a frame, a block supporting member, a bonnet supporting member, a lever pivoted to said frame between its ends and operatively connected to said members at its respective ends, a cam follower on said lever, a control shaft and an actuating cam on said shaft engaging said cam follower.

3. In a hat shaping machine as claimed in claim 2, a counterweight on said lever adapted to urge said bonnet supporting member upwardly whereby said block supporting member is allowed to move downwardly.

4. A hat shaping machine as claimed in claim 2, wherein said cam comprises a lowered position corresponding to the lowered position of said block supporting member and the elevated position of said bonnet supporting member, a raised circular portion corresponding to the reverse position of said members, and a series of notches on a portion at least of said circular portion to cause a 120 jerky motion of said members.

5. In a hat shaping machine, a control shaft, a driving member, clutch means between said shaft and said member, a perforated block adapted to receive the hat blank,

means for circulating steam through said block and hat blank, valve means for controlling said circulating means, stretching means operable by said shaft for stretching the hat blank on said block, means on said shaft for bringing said clutch means to the unclutching position upon completion of the movement of said stretching means into the operative position, a control member for re-clutching said clutch means, means on said shaft, operative upon re-clutching of said clutch means, for closing said valve means, and means on said shaft for re-unclutching said clutch means upon return of said stretching means to the idle position.

6. In a hat shaping machine, a frame, a block adapted to receive the hat blank, a circular row of clamping members pivoted to said frame and adapted to clamp the edge of the hat blank, a joint line forming collar adapted for axial movement to engage said hat blank between said block and clamping members, inner projections on said clamping members, and an axially movable control member engaging said projections for controlling the pivotal movement of said clamping members, the pivots for said clamping members being arranged in a common transverse plane and said projections having curved surfaces of varying radii in the several projections, respectively, whereby the operative parts of said clamping members are arranged in an oval when said projections engage said control member.

7. In a hat shaping machine, clamping means adapted to clamp the edges of the hat blank, means for controlling the clamping action of said clamping means, a shaft, a cam member on said shaft adapted to operate said controlling means, a manually operated actuating member on said shaft, shaft rotating means, a driving shaft and a cam member on said driving shaft adapted to actuate said shaft rotating means for releasing said clamping means upon completion of the machine operative cycle.

8. A hat shaping machine as claimed in claim 7, wherein the controlling means for said clamping means comprise a pivoted strap embracing said first-mentioned cam member, and means for adjusting the position of the pivot axis of said strap, for adjusting the clamping action of said clamping means.

9. In a hat shaping machine, a number of pivotal clamping members adapted to clamp the edge of the hat blank, a movable member for controlling the pivotal movement of said clamping members, means embodying an oscillating lever for actuating said movable member, a segment having a recess at its periphery, a latch pivoted to said lever and adapted to ride over said segment and engage said recess in a predetermined position of said lever, and means for adjusting the angular position of said segment for locking

said clamping members in adjustable positions.

10. In a hat shaping machine as claimed in claim 2, air circulating means, valve means for controlling said air circulating means, a valve controlling lever pivoted to said first-mentioned lever and adapted to actuate said valve means, a cam follower on said valve controlling lever and a cam member on said shaft engaging said cam follower.

In testimony whereof I have signed my name to this specification.

MARCEL CASSE.
